CLAIM

The ornamental design for a pump spray container, as shown and described.

DESCRIPTION

FIG. 1 is a front elevational view of a pump spray container showing our new design, the rear elevation is a mirror image thereof;

FIG. 2 is a right side elevational view, which is a mirror image of the left side view;

FIG. 3 is a top plan view thereof; and,

FIG. 4 is a bottom view thereof.

The broken lines showing a pump dispenser nozzle and an overcap are for illustrative purposes only and form no part of the claimed design.

FIG. 1.

FIG. 2.

FIG. 3.

FIG. 4.
